UNITED STATES PATENT OFFICE.

DOUGLAS VON ARNHEM, OF BERLIN, GERMANY.

BOOT OR SHOE PROVIDED WITH UPPER SECTIONS OF DIFFERENTLY-COLORED MATERIAL.

1,413,508.

Specification of Letters Patent. Patented Apr. 18, 1922.

Application filed November 29, 1920. Serial No. 427,222.

To all whom it may concern:

Be it known that I, DOUGLAS VON ARNHEM, a citizen of the German Republic, and a resident of Berlin, Germany, have invented 5 certain new and useful Improvements in Boots or Shoes Provided with Upper Sections of Differently - Colored Material, of which the following is a specification.

The present invention relates to boots or 10 shoes, the uppers of which are made up of sections of differently colored leather or leather and cloth or other textile material and consists in providing a strip or fillet, between said sections so that those sections 15 which require different cleaning or polishing treatment, can be dealt with without detriment to each other.

In the accompanying drawing in which the invention is illustrated by way of example,

Fig. 1 represents a view of a boot made according to the invention, while

Figs. 2 to 6 are sectional views, showing various methods of putting the invention in 25 to practice.

The portions *a* and *b* of the boot or shoe according to Fig. 1 are made of different material and color. For instance the portion *a* may be made of ordinary leather which 30 requires the usual polishing, and the portion *b* may be made of cloth. To enable the portion *a* to be polished without detriment to the portion *b*, a strip or fillet *c* is run along the junction between said two portions, so as 35 to prevent the polish from spreading from one portion to the other. A strip or fillet may be made separately, preferably out of patent leather, so as to be itself unaffected by the polish and this strip or fillet may 40 either overlap the adjacent sections of the

boot material as shown in Fig. 3 or be arranged contiguous therewith as shown in Fig. 4. The overlapping protecting strip in Fig. 2 is formed with a raised edge *d* at the side where the polish is to be retained. In 45 Fig. 5 another overlapping strip is beaded so as to form a raised protecting fillet. The strip in Fig. 6 is connected like a flap, so that it can be turned up, as shown in dotted lines, while the polish is applied to the lower 50 section.

The raised strip or fillet also serves as a guide for the polishing implement and prevents the latter from coming into contact with the part which is to be protected. 55

It is already known to provide boots and shoes with quilted seams, but these are ordinarily made to serve as ornaments and are not capable of protecting adjacent sections of the boot material from the polish like the 60 protecting strip according to the present invention.

Having thus particularly described the nature of my invention, what I claim as new and desire to secure by Letters Patent of the 65 United States is:

In boots or shoes having sections of differently colored leather or of leather and other material, the arrangement of a protecting strip or raised fillet, said strip or 70 fillet being provided between said sections, so as to protect one section from the polish applied to another section.

In testimony whereof I affix my signature in presence of two witnesses.

DOUGLAS VON ARNHEM.
